(57) **CLAIM**

The ornamental design for a pattern for sanitary article, as shown and described.

DESCRIPTION

FIG. 1 is a plan view of a first embodiment of a sanitary article top showing my new design; and,

FIG. 2 is a plan view of another embodiment thereof. The broken lines shown in FIGS. 1 and 2 illustrate portions of the pattern for sanitary article that form no part of the claimed design.

The gray coloration indicates a contrast in appearance.
